ELECTRONICALLY TIMED RELAY

Spencer A. Tucker, New York, and Alvin W. Gellert, Rego Park, N. Y.

Application February 20, 1947, Serial No. 729,776

8 Claims. (Cl. 175—320)

1

Our present invention relates to an electronic timer and aims to provide certain improvements therein. More specifically, it relates to a timer designed particularly for photographic contact printers, enlargers, blue printing machines, photostat making machines, etc., although it is equally well adapted for use in other industrial and scientific fields wherein any type of electrical apparatus or device is to be operated for a predetermined interval of time.

Electronic timing devices are known and have been used for many years in the photographic and industrial fields. In all of these prior devices of which we have knowledge, the accuracy of the selected time interval, the time range, or the means for setting the time interval are not entirely satisfactory because they are unreliable, too costly, or require a bright light for increased visibility or extreme care for setting means which govern the timing interval.

The foregoing objectionable features of prior devices are overcome by our present invention according to which upon the closing of an initiating switch in a vacuum tube circuit, electric current is caused to flow through a load circuit, and after a predetermined time interval which is governed by the rate of discharge of capacitance through resistance in the vacuum tube circuit, the flow of current through the load circuit is automatically cut off. After completion of the desired operation by the device within the load circuit, the timer is ready for the next operation, which can be initiated by again merely operating the initiating switch. The invention which includes a modified Eccles-Jordan trigger or "flip-flop" circuit having therein a relay, an initiating switch and an adjustable resistive-capacitive network will be better understood from the detailed description which follows when considered in connection with the accompanying drawings wherein:

Fig. 1 shows a preferred circuit diagram for the electronic timing device embodying our invention; and

Fig. 2 is a diagrammatic showing of our novel time selector switch assembly illustrating one arbitrary setting of the switch members thereof.

Referring to Fig. 1 of the drawings, electric current, either A. C. or D. C., is supplied to the device by inserting a connector plug 10 into a suitable outlet receptacle (not shown). One of the leads from the plug is connected through a manually operable switch 11 to a ground or common connection in said circuit. The other lead from the plug which completes the circuit is connected to the heater elements and to the plates

2

of the diode sections of a pair of vacuum tubes 12 and 13, or any equivalent rectifier, in a conventional manner to provide half wave rectification where A. C. is employed. As herein shown, the cathodes of the said diode sections of the vacuum tubes are connected together and also connect with the plates and the screen grids 14 and 15 of the pentode sections of said vacuum tubes 12 and 13 respectively or the corresponding elements of other electron tubes. Within the branch circuit connecting with the plate of the pentode section of tube 12 is a relay 16 and a voltage dropping resistor 17 which properly matches the output characteristics of tube 12. Within the branch circuit connecting with the cathodes of the diode sections of tubes 12 and 13 is a filtering condenser 18. Within the branch circuit connecting with the screen grid 15 are resistors 19 and 20. The cathodes of the pentode sections 20 of tubes 12 and 13 are connected together and in said connecting line there is connected a potentiometer 21 which serves as a calibration control which determines the critical point at which the circuit will flip or trigger. The contact arm 25 of the potentiometer is connected to ground through a resistor 22. Connected to the line leading to the plate of the pentode section of tube 12 is a branch circuit containing a manually controlled, self-opening, initiating switch 23 controlled by a spring 23a, a condenser 24, a second condenser 25 and a resistor 26. Coupled in the circuit between the two tubes 12 and 13 is an adjustable capacitive-resistive arrangement or network herein shown as consisting of a timing condenser 27, and a time selector switch assembly indicated generally by the numeral 28, which latter is interposed between the control grid 29 of tube 13 and the cathode of tube 13. A power receptacle outlet 30 is adapted to be connected 40 to the power source when the relay 16 is energized by the closing of the switch 23. The outlet 30 is also adapted for direct connection with the power source independently of the timing circuit, through the connector plug 10 and for this purpose a manually controlled switch 31 is inserted 45 in this separate circuit. In photographic use, the switch 31 would be used for focusing the enlarger prior to initiating the timing cycle. A neon pilot lamp 31a with a proper voltage dropping resistor 31b may be provided for furnishing sufficient illumination for setting the push buttons of the selector switch 28 and for other purposes. 50 The relay 16 is preferably of the double pole, double throw type, having its poles 32 and 33 shown as spaced from the armature 16a of relay 16 for clarity of illustration and said poles are 55

adapted when the relay is energized to make contact with contacts 34 and 35 respectively, which in turn connect with the control grid 29 of tube 13 and a lead to the power outlet 30 respectively.

The time selector switch assembly 28 as shown in Fig. 2 contains seven push button switches 36 to 42 inclusive, controlling resistors 43 to 49 respectively and provides a resistive-capacitive network with the condenser 27 which has a special low leakage characteristic. The switches 36 to 42 are preferably of the push button type, each being a single pole, single throw, normally closed switch. Each of the switches is shunted across a resistor which it controls. When no button is depressed all seven resistors are short-circuited. By depressing any one of the seven buttons or switches, the corresponding resistor is admitted into the circuit. Depressing any combination of these switches places the corresponding resistors in series thereby increasing the time constant of the network. The resistors 43 to 49 in the ascending order of their designating numbers are preferably so chosen that the admitting of resistor 43 will have a time constant discharge of one second, resistor 48 a time constant of two seconds, and each succeeding resistor a time constant twice as large as its preceding numbered resistor. In other words the time constants of the resistors 43 to 49 are in geometrical progression. With seven resistors as shown it will thus be seen that by admitting one or more of them any time constant for discharge of condenser 27 from 1 second to 127 seconds, in one second steps, can be obtained. It will also be apparent that by increasing the number of buttons and resistors the time selector range may be increased indefinitely, each additional switch and resistor doubling the range of the timer achieved with the previous number of switches. As shown in Fig. 2 switches numbered 36, 37, 39 and 40 are open thus providing for the sum of timing constants of 1, 2, 8 and 16 seconds or a 27 second timing interval for discharge of the condenser 27. Although push button switches are referred to, it will be obvious that toggle switches, lever switches or any other switching mechanism may be employed. It will also be apparent that if desired a decade multiplier switch may be coupled with a plurality of timing condensers whereby the time intervals provided by the switches 36 to 42 may be changed in decade steps.

In the circuit shown and described, the cathode of each diode section of the tubes is positive and the high capacitance of condenser 18 acts to smooth any voltage pulsations resulting in a D. C. of lower ripple content. As a result of rectification, a positive D. C. voltage is impressed on the plate and on the screen grid of each pentode section of each tube. The resistor 17 and relay 16 provide a path for the positive voltage to appear on the plate of tube 12 and the resistor 19 provides continuity of a positive voltage on screen grid 15. The potentiometer 21 is the calibration control which determines the critical point at which the circuit will flip or trigger. Condenser 24 is used to prevent arcing and pitting of the contacts at switch 23. Resistor 26 serves to discharge condenser 25 so that it will be ready to accept a new initiating voltage charge. Resistors 19 and 20 provide the correct voltage for the screen grid 15.

Operation.—Upon inserting plug 10 into a socket supplying electric current, either A. C. or D. C. and then closing switch 11, rectified

and filtered D. C. is supplied to the modified Eccles-Jordan vacuum tube circuit containing tubes 12 and 13. In the quiescent state of the timer, tube 13 will be conducting current and tube 12 will be non-conducting. The desired time interval is chosen by actuating the proper switch or combination of switches in the time selector switch assembly 28, which in turn admits into the circuit the corresponding value of resistance from the resistors 43 to 49. The timing cycle is initiated by momentarily closing the starting switch 23. Instantaneously upon the closing of the starting switch, the relay 16 is caused to close by virtue of a high initial charging current of starting condenser 25 flowing through the relay 16. The instant the relay closes, the poles 32 and 33 thereof engage contacts 34 and 35 respectively. Contact between pole 33 and contact 35 completes the circuit from the power source to receptacle 30 thereby supplying current to the load circuit at the power receptacle 30. Simultaneously, contact between pole 32 and contact 34 causes vacuum tube 13 to cease drawing current as a result of an applied negative voltage on the control grid 29 from the negative side of condenser 27. Since vacuum tube 13 is now not conducting, a positive voltage which previously existed at the cathode of the pentode section of tube 12 is no longer present, thus causing vacuum tube 12 to conduct and resulting in a flow of plate current through the relay 16 thereby keeping the relay energized. While vacuum tube 12 is conducting (and the relay is closed) the negative voltage which appears at the control grid 29 of tube 13 is diminishing at a rate determined by the value of the resistance selected with the time selector switch 28. When this negative voltage has dropped to such a value which will permit vacuum tube 13 to conduct, a positive voltage will be placed at the cathode of the pentode section of vacuum tube 12 causing the current which was flowing through said vacuum tube and through the relay 16 to cease, thereby releasing the relay armature thus breaking contact at points 34 and 35 and breaking the current flow to the load circuit. The timing cycle is thus completed and the timer is now ready for another cycle.

The timer can be used with a D. C. source of current, in which case the direct current is pure and unvarying and the diode sections of the vacuum tubes will pass current continuously instead of only half the time when A. C. is used.

While it will be understood that the circuit specifications of the electronic timer may vary according to the design for any particular application, the following circuit specifications for a timer particularly suitable for photographic printing and the like are included by way of example only, as follows:

Resistors

17	17K, 2W, 5%
19	20K
20	30K
22	1500, 2W, 5%
26	150K
31b	150K, 10%
43	0.159 megohms, 2%
44	0.318 megohms, 2%
45	0.636 megohms, 2%
46	1.270 megohms, 2%
47	2.54 megohms, 2%
48	5.10 megohms, 2%
49	10.20 megohms, 2%

All resistor values in ohms $\frac{1}{2}$ W, 5% unless otherwise indicated.

The relay 16—2500 ohm coil; 5 ma. closed; 2 ma. open; 10 amp. 125 v. A. C.

The potentiometer 21—1000 ohms, 2W.

Capacitors

18—20 mfd. 150 v.—electrolytic
24—0.1 mfd. 200 v.—paper tubular
25—10. mfd. 150 v.—electrolytic
27—3.0 mfd. 5% 200 v. oil filled paper

The vacuum tubes 12 and 13 are type 117 N7GT.

While we have shown and described what we believe at present is considered the preferred embodiment of our invention, it will be obvious to those skilled in the art that various changes and modifications may be made therein without departing from the spirit of the invention as defined in the appended claims.

What we claim is:

1. An electronic timer for controlling the energization of a load circuit comprising a flip-flop trigger circuit including first and second electron discharge tubes each provided with a cathode, a control grid and an anode, and circuit means to apply positive potentials with reference to ground to the respective anodes of said tubes, said first tube being normally non-conductive and said second tube being normally conductive, a relay including an electromagnetic winding and a switch actuated thereby, said winding being interposed in the anode circuit of said first tube, said switch having first and second contact positions and normally occupying said first position, a timing condenser having one end connected to the anode of said first tube and the other end connected selectively through said switch in the first position to ground and through said switch in the second position to the control grid of the second tube, said condenser attaining a charge when connected to ground, a variable resistance element for discharging said condenser and connected between the control grid and the cathode of said second tube, means to apply momentarily an energizing current through said winding to actuate said switch and connect said condenser to the control grid of the second tube, the charge on said condenser rendering said second tube non-conductive whereby said first tube is rendered conductive, the conduction through said first tube maintaining said winding energized for a period determined by the time constant of said condenser and said element, and means responsive to the actuation of said switch for energizing the load circuit.

2. An electronic timer for controlling the energization of a load circuit comprising a flip-flop trigger circuit including first and second electron discharge tubes each provided with a cathode, a control grid and an anode, and circuit means to apply positive potentials with reference to ground to the respective anodes of said tubes, said first tube being normally non-conductive and said second tube being normally conductive, a relay including an electromagnetic winding, said winding being interposed in the anode circuit of said first tube, a main and an auxiliary switch actuated thereby, said main switch having first and second contact positions and normally occupying said first position, said second switch being normally open, a timing condenser having one end connected to the anode of said first tube

and the other end connected selectively by said main switch in first position to ground and in the second position to the control grid of the second tube, said condenser attaining a charge when connected to ground, a variable resistance element for discharging said condenser and connected between the control grid and the cathode of said second tube, means to apply momentarily an energizing current through said winding to actuate said main switch and connect said condenser to the control grid of the second tube, the charge on said condenser rendering said second tube non-conductive whereby said first tube is rendered conductive, the conduction through said first tube maintaining said winding energized for a period determined by the time constant of said condenser and said element, and a source of energizing voltage for said load circuit connected thereto through said second switch, said load being connected as long as said winding is energized.

3. An electronic timer for controlling the energization of a load circuit comprising first and second electron discharge tubes each provided with a cathode, a control grid and an anode, a source of direct-current potential for said tubes, the negative end of said source being connected to ground, a voltage-dropping impedance, a relay including an electromagnetic winding and a switch actuated thereby, said switch having first and second contact positions and normally occupying said first position, the positive end of said source being connected to the anode of said second tube and in series with said winding and said impedance to the anode of said first tube, a bias resistor connected between ground and the cathodes of said tubes, the potentials normally on the electrodes of said tubes having values at which said second tube is conductive and said first tube non-conductive, a timing condenser having one end connected to the anode of said first tube and the other end connected selectively by said switch in the first position to ground and in the second position to the control grid of said second tube, said condenser attaining a charge when connected to ground, means connecting the control grid of said first tube to ground, a variable resistance element for discharging said condenser and connected between the control grid and cathode of said second tube, means to apply momentarily an energizing current through said winding to actuate said switch and connect the charged condenser to the control grid of said second tube to render same non-conductive whereby said first tube is rendered conductive, the conduction through said first tube maintaining said winding energized for a period determined by the time constant of said condenser and said element, and means responsive to the actuation of said switch for energizing the load circuit.

4. An electronic timer, as set forth in claim 3, wherein said means to apply momentarily an energizing current through said winding includes a capacitor and self-opening switch connected in series with said capacitor between ground and the junction of said impedance and said winding.

5. An electronic timer, as set forth in claim 3, wherein said variable resistance element includes a plurality of serially-connected resistors having mutually different values and a like plurality of switches each connected in shunt relation with a respective resistor.

6. An electronic timer, as set forth in claim 5, wherein the successive values of said serially-con-

connected resistors differ in accordance with a geometrical progression.

7. An arrangement, as set forth in claim 3, wherein said impedance has a value substantially matching the output impedance of said first tube.

8. An electronic timer for controlling the energization of a load circuit comprising first and second electron discharge tubes each provided with a cathode, a control grid and an anode, a source of direct-current potential for said tubes, the negative end of said source being connected to ground, a voltage-dropping impedance, a relay including an electromagnetic winding and a switch actuated thereby, said switch having first and second contact positions and normally occupying said first position, the positive end of said source being connected to the anode of said second tube and in series with said winding and said impedance to the anode of said first tube, a potentiometer having an adjustable arm and interconnecting the cathodes of said tubes, a bias resistor connected between ground and said adjustable arm, the potentials normally on the electrodes of said tubes having values at which said second tube is conductive and said first tube non-conductive, a timing condenser having one end connected to the anode of said first tube and the other end connected selectively by said switch in the first position to ground and in the second position to the control grid of said second tube, said condenser attaining a charge when connected to ground, means connecting the control grid of said first tube to ground, a variable resistance element for discharging said condenser and connected between the control grid and cathode

5 of said second tube, means to apply momentarily an energizing current through said winding to actuate said switch and connect the charged condenser to the control grid of said second tube to render same non-conductive whereby said first tube is rendered conductive, the conduction through said first tube maintaining said winding energized for a period determined by the time constant of said condenser and said element, and means responsive to the actuation of said switch for energizing the load circuit, said last named means including an auxiliary switch actuated by said winding.
